UNITED STATES PATENT OFFICE.

CHARLES L. GOODRUM, OF BROOKLYN, NEW YORK, ASSIGNOR TO WESTERN ELECTRIC COMPANY, INCORPORATED, OF NEW YORK, N. Y., A CORPORATION OF NEW YORK.

FINDER-STARTING SYSTEM.

1,330,464.

Specification of Letters Patent. Patented Feb. 10, 1920.

Application filed September 22, 1916. Serial No. 121,572.

To all whom it may concern:

Be it known that I, CHARLES L. GOODRUM, a citizen of the United States, residing at Brooklyn, in the county of Kings and State 5 of New York, have invented certain new and useful Improvements in Finder-Starting Systems, of which the following is a full, clear, concise, and exact description.

This invention relates to telephone exchange systems employing line finder switches, and more particularly to systems in which a starter wire arrangement is used in conjunction with such switches.

The object of the present invention is to 15 provide an arrangement whereby calls originating in the same group may be handled at an increased speed.

Heretofore in systems employing line finders, it has been the practice to permit 20 only one finder to start seeking a calling line in a given group at a time. Although means have been provided for responding immediately to a second call if in a group other than that of the first calling line, 25 means have been provided for delaying the response to the second call when in the same group, in some systems until the first calling line has been reached, in other systems until a time measuring switch has been fully operated 30 in order to measure an interval slightly greater than the time required for the brush set to travel to the last line of a group, and in certain systems until the first switch to be started has moved out of its normal 35 position.

A feature of the present invention is the provision of means for starting a number of line finders simultaneously when a number of calls in the same group are originated 40 at the same time. This is accomplished by the operation of a marginal relay which fails to operate when only one call is present. The actuation of this relay results in placing ground on the out-starter wire 45 immediately, without waiting for the in-starter wire to be extended thereto, as is usual in systems of this type.

The invention as shown is arranged for use with a circuit arrangement such as 50 shown in Patent No. 1,147,390, issued July 20, 1915. The switch structure in the present embodiment is, however, of the around-and-up type, whereas the structure of the switch in the above mentioned patent is of 55 the well-known up-and-around type. This

necessitates no change in circuit arrangement, the only change being that instead of using a group multiple commutator whose segments are arranged in a straight line, a commutator whose segments are arranged 60 in a circle is used.

It is thought that the invention will be best understood from the following detailed description, reference being had to the accompanying drawing.

In the drawing the lines of two calling subscribers in the same group are represented, together with such portions of a finder circuit and starter wire arrangement as are necessary to an understanding of the 70 invention.

If the subscriber at substation 1 desires to initiate a call he removes his receiver from the hook, whereupon line relay 2 is energized over a circuit from grounded battery, right-hand winding of relay 2, right-hand armature and back contact of cut-off relay 3, through the line loop and substation apparatus of the calling subscriber, left-hand armature and back contact of relay 3, left-hand winding of relay 2, to ground. Relay 2 attracts its armature and completes a circuit for group relay 4 from grounded battery, winding of relay 4, conductor 5, resistance 6, to ground at the armature and front contact of relay 2. Relay 4 is energized and attracts its armatures. The attraction of the left-hand armature of relay 4 completes a circuit for group relay 7, but this relay, being marginal, does not 85 operate, due to the presence of resistance 6. The outer right-hand armature and front contact of relay 4 supplies ground through contact 8 of the finder indicated to the right of the dotted line to the primary magnet of 90 such switch. The primary magnet of the switch is operated over circuits such as disclosed in the previously mentioned Patent No. 1,147,390. When commutator brush 9 arrives on a segment 10 on which there is 100 no ground, due to the actuated condition of relay 4, the circuit of the primary stepping magnet will be permanently interrupted and the brush set 11 will be positioned in proper relation to the group of terminals containing the calling line. The side switch, one of whose wipers is indicated at 12, is moved into position 2.

In position 2 brush set 11 is moved over terminals in the desired group by the oper- 110

ation of a secondary stepping magnet. When line test brush 13 engages an ungrounded test terminal 14, the circuit of the stepping magnet will be permanently interrupted and the side switch will move into position 3.

In position 3 of the side switch cut-off relay 3 is energized to remove the control of the line relay from the calling subscriber.

10 It is to be noted that when starter wire 15 has been connected to out-starter wire 16, through off-normal contact 17 and side-switch wiper 12 in its third position, a second call coming in at this time will start a 15 succeeding finder whether such call is originated in the group shown or in a preceding group.

If it should happen that the subscribers at sub-stations 1 and 21 should originate 20 calls simultaneously, line relays 2 and 22 will be energized in the well-known manner. Group relay 4 will be energized as previously described. A circuit is completed at this time for relay 7 from grounded battery, winding of relay 7, left-hand armature and front contact of relay 4, to ground, through resistances 6 and 26 in parallel. The reduced resistance in this path allows 25 marginal relay 7 to energize, whereupon a circuit is completed from ground, armature and front contact of relay 7, side-switch wiper 12 in its first position, out-starter wire 16, to the primary magnet of the next 30 idle finder. The actuation of relay 4 starts 35 the finder shown in the drawing as previously described, and it will therefore be seen that two finders have been started at the same time.

A call coming in from a preceding group 40 over in-starter wire 15 will await the arrival of side-switch wipers 12 in position 3 at both switches, whereupon it will start the finder normally allotted to the second succeeding group, if idle. When the lines are 45 found, the deenergization of line relays 2 and 22 breaks the circuit of relay 4 which deenergizes and opens in turn the circuit of relay 7. The deenergization of relay 4 places ground on group commutator segment 10 to indicate the non-calling condition thereof. Group relays 4 and 7 may now 50 be again actuated in response to other calls originating in the same group.

At conclusion of the conversation an actuated finder is restored in the manner set forth in the previously mentioned patents.

What is claimed is:

1. In a telephone exchange system, a plurality of calling substation lines arranged in groups, a plurality of finder switches 60 serving said lines, there being a finder switch normally assigned to each of said groups, and means to start a plurality of finders simultaneously in search of lines calling in the same group at the same time. 65

2. In a telephone exchange system, a plurality of calling substation lines arranged in groups, a plurality of finder switches serving said lines, a relay for each of said groups to control the starting of one of 70 said finders, a second group relay to control the starting of a second finder, and means to energize said second relay only when more than one call is present in the group with which it is associated. 75

3. In a telephone exchange system, a plurality of calling substation lines arranged in groups, a plurality of finder switches serving said lines, a relay for each of said groups, a second group relay controlled at 80 contacts of said first relay, means to start two of said finders simultaneously when both of said relays are energized, and means to energize both of said relays when more than one call is present in the group with 85 which said relays are associated.

4. In a telephone exchange system, a plurality of calling substation lines arranged in groups, a plurality of finder switches serving said lines, there being one of said finder switches normally assigned to each of said groups, a starter wire circuit to control the starting of the switch of a succeeding group when the switch normally assigned to the group in which the call originates is 95 busy, means to extend said starter wire to a succeeding switch when a calling line is seized, and means to operate a succeeding switch without awaiting the extension of the starter wire when two calls are originated 100 in the same group at the same time.

In witness whereof, I hereunto subscribe my name this 19th day of September A. D., 1916.

CHARLES L. GOODRUM.
